UNITED STATES PATENT OFFICE.

DANIEL S. WILSON, OF WEST SOMERVILLE, MASSACHUSETTS, ASSIGNOR TO SAMSON ELECTRIC COMPANY, OF CANTON, MASSACHUSETTS, A CORPORATION OF MASSACHUSETTS.

POLARIZED SIGNALING MECHANISM.

1,300,539.

Specification of Letters Patent. Patented Apr. 15, 1919.

Application filed May 11, 1917. Serial No. 167,895.

To all whom it may concern:

Be it known that I, DANIEL S. WILSON, a citizen of the United States, residing at West Somerville, county of Middlesex, State of 5 Massachusetts, have invented an Improvement in Polarized Signaling Mechanism, of which the following description, in connection with the accompanying drawing, is a specification, like characters on the drawing 10 representing like parts.

This invention relates to improvements in signaling mechanism and the general object of the invention is to provide a synchronous vibrating signaling device which will be instantly 15 responsive when the desired signal is given and which will be certain and reliable in operation.

More specifically the main object of the invention is to produce a signaling device, 20 preferably a horn, operable by an alternating current, which will be adapted for general or code signaling and which will instantly produce a desired tone of maximum volume without the "picking up" which 25 usually attends the operation of signal horns of this character.

Experience has shown that signaling devices, particularly horns operated by an alternating current, even though carefully 30 tested out at the factory before their installation and also found to operate satisfactorily for a time, have soon developed serious defects such as refusing to start or of "stuttering," breaking springs, or getting out of 35 adjustment, so that they can not be depended upon to give instant service. Such defects are of course, fatal in horns which are used for fire signals and other purposes in which 40 reliability is a prime requisite.

Furthermore, such horns usually require an appreciable period of time to pick up in vibration sufficiently to give the desired sound, and the full volume of sound. The present invention is designed to overcome 45 these and other defects and to provide a synchronous vibrating signaling mechanism embodying the principle of operation by which the signal may be instantly started to produce the desired tone at its maximum 50 volume and which will be instantly stopped upon the interruption of the actuating current.

A further feature of the invention con-

sists in producing a signaling device of this character which will require a minimum 55 amount of energy for its operation.

Another object of the invention is to produce a polarized synchronous vibrating signaling mechanism in which the actuating mechanism comprises permanent magnets 60 with a coöperating armature influenced by an alternating current in such a manner that the action of the alternating current will not de-magnetize the magnets, as inevitably occurs in signaling devices heretofore produced in which an alternating magnetic circuit is included in the series with the magnetic circuit of the permanent magnet. 65

This is accomplished by providing a plurality of continuous magnetic circuits produced either by permanent or electro-magnets and so disposed relatively to an armature common to the magnets that the magnetic flux produced by an alternating current passing around the armature is 70 forced alternately in the direction of the normal magnetic flux of the continuous or permanent magnetic circuits and practically 75 no magnetic flux forced in a direction opposite to that of either permanent field. 80

Another object of the invention is to provide a signaling horn mechanism in which two diaphragms may be vibrated with approximately the same current consumption required for one, thus in effect producing 85 two horns capable of giving double the volume of sound of a single horn at about the expense of one.

Another object of the invention is to produce a signaling horn of the character described in which the diaphragm has a natural period of vibration equal to the number of alternations of the operating current or a perfect multiple of that number. The vibration of the diaphragm thus being in synchronization with the frequency of alternation of the current avoids opposition between the movement of the diaphragm and the mechanism which operates the diaphragm. 90 95

The drawings illustrate certain preferred 100 embodiments of my invention as applied to a double signaling horn adapted for general use but particularly designed for fire signaling apparatus.

In the drawings, 105
Figure 1 is an elevation partly in section

showing a preferred embodiment of my invention as applied to a double signaling horn,

Fig. 2 is a transverse sectional view of the 5 magnets and armature on line 2—2, Fig. 1,

Fig. 3 is a longitudinal vertical sectional view of the armature shown in Fig. 1 and,

Fig. 4 is an elevation of a modified form 10 of signal actuating mechanism, illustration of the horns having been omitted.

The preferred embodiments of my invention 15 illustrated in the accompanying drawing comprise a polarized synchronous vibrating horn mechanism having permanent magnets with their opposite poles juxtaposed and a common armature located between adjacent poles of said magnet, means being provided for passing an alternating current around said armature in such a manner 20 as to produce a magnetic flux alternately in opposite directions so that this flux in co-operation with the magnetic flux of the fields of the magnets will cause a vibration or reciprocation of the armature. This vibration of the armature is transmitted to the diaphragms of oppositely disposed sound projectors.

The magnets are illustrated in the accompanying drawings as permanent magnets but 30 it will be understood that suitable electromagnets may be utilized in the place of the permanent magnets within the meaning and scope of the invention disclosed herein. Certain structural features are common to the 35 embodiments of the invention illustrated in the accompanying drawings and like parts will be designated by the same numerals in the structures illustrated in both Figs. 1 and 4.

40 The actuating mechanism is mounted within a hollow preferably rectangular metallic casing having a bottom 1 and sides 2, 3, 4 and 5 provided with ears 6 for attachment to a suitable base or wall and a cover, 45 (not shown). The actuating mechanism comprises a pair of complementary U-shaped magnets 7, 8 which are supported from the bottom 1 of the casing and suitably insulated therefrom, the opposite poles of said magnets being juxtaposed so that the north pole N of the magnet 7 is opposite the south pole S' of the magnet 8 and the south pole S of the magnet 7 opposite the north pole N' of the magnet 8, the poles of the magnets being 55 separated only a sufficient distance to accommodate the armature and permit of its vibration. The armature 9 desirably is in the form of a rectangular bar pivotally mounted upon an axis 10 located centrally between 60 said magnets and disposed symmetrically between the opposing poles thereof.

One end of the armature is prolonged to form an extension 11 projecting beyond one pair of the juxtaposed poles, the projecting 65 end preferably being faced with hardened

plates 12 to act as hammers upon the means for vibrating the diaphragms of the horn as will hereinafter more fully appear.

The armature is actuated by an alternating current which passes through a suitable coil 70 13 surrounding the armature 9, preferably two coils 13, 14, located upon opposite sides of the pivot 10 being provided and these coils wound in such a manner that when the alternating current is impressed upon them both ends of the armature will have the same polarity, that is to say, the ends of the armature will be alternately simultaneously, both north and both south. Therefore, when the alternating current is passed through the coils a magnetic flux will be produced which will cooperate alternately with the fields of the respective magnets to cause a vibration of the armature in synchronization with the alternations of the current. 75 80 85

Any suitable form of signaling mechanism may be actuated by the vibrating armature, the preferred signaling means illustrated in Fig. 1 being horn diaphragms 15 90 disposed upon opposite sides of the casing. The projectors of the horns may be turned in any direction but as illustrated are directed oppositely. Of course a single horn may be used if desired. 95

The horns illustrated herein comprise concaved base plates 16, secured to the opposite side walls 2, 3 of the casing and have annular flanges 17 to which complementary concaved plates 18, having flanges 19 are secured 100 by screws 20 or other suitable fastening means. The periphery of the diaphragm 15 may conveniently be clamped between the flanges 17 and 19. The central portion of the plates 18 are provided with outwardly 105 extending flanges 21 to which the smaller ends 22 of the usual projectors 23 of the horns are secured, either permanently or rotatably, so that the same may be disposed in any direction in which it is desirable to project the sound. 110

Any suitable means may be provided for transmitting the vibration of the armature to the diaphragms, a convenient means which is shown in Fig. 1 comprises rods 24 115 rigidly secured to the centers of the diaphragms 15 and pass through apertures 25 in the plates 16 and the adjacent casing walls 2 and 4. Desirably bearings are provided in extensions 26 of brackets or sleeves secured to the ends of the magnets 7, 8. 120

The ends of the rods 24 desirably are provided with hardened heads 28 preferably having curved faces adapted to be struck by the hammer plates 12 of the armature 125 extension 11.

The armature preferably is so mounted and balanced that its center of percussion is located in the line of impact of the hammer plates 12 with the heads 28, thereby prac- 130

tically eliminating the vibration of the armature which would otherwise result from the impact of the armature with the heads 28 and thus reducing the strain upon the pivot 5 to a minimum.

The diaphragms preferably are constructed of such material and are of such dimensions as to diameter and thickness that the relation of the mass, the dimensions and the 10 modulus of elasticity of the diaphragms is such as to give the diaphragms a natural period of vibration corresponding, or equal to the number of alternations of the operating current or a perfect multiple of the number 15 of such alternations.

By thus synchronizing the normal vibrations of the diaphragm with the frequency of alternation of the current the resistance of the diaphragms to the impulse produced by 20 the vibrating armature is reduced to a minimum and the maximum vibration of the diaphragms produced with the least possible consumption of energy. Furthermore, by this 25 synchronization between the diaphragms and the vibrating armature all interference with the normal vibration of the diaphragms is eliminated and consequently a pure tonal vibration of said diaphragm insured.

In signaling horns actuated by an alternating current in which permanent magnets have been employed the electro-magnetic circuit has been included in series with the permanent magnetic circuit and as a result of this construction the permanent magnets soon 30 have become de-magnetized and the signaling mechanism rendered inoperative. By the present invention a plurality of permanent magnetic circuits are utilized and so disposed as to make it possible for the flux produced by 35 the alternating current to alternate first from one permanent magnetic circuit to another so that practically no flux is forced through either permanent magnetic circuit in opposite direction to that of the permanent field. 40 The simpler structure embodying this principle is illustrated in Fig. 4 in which the magnetic circuit of one of the magnets is illustrated by a series of arrows, the flux of the complementary magnet being of course, 45 in the opposite direction.

If the momentary direction of the current is such as to polarize both ends of the armature north as indicated, the armature will rotate on a pivot in a clockwise direction and 50 upon reversal of current the armature will be caused to rotate in opposite or counterclockwise direction. This movement of the armature may be caused to impart a vibration to the diaphragm of the horn as above described 55 or to actuate any other desirable type of signal.

By this construction the flux caused by the alternating current will alternate from one magnetic circuit to the other so that practically 60 no flux will be forced in either the

right or left hand circuit in a direction opposite to that of the permanent field and thus no demagnetizing effect will be produced upon the permanent magnets, and the reliability of the signaling mechanism will be 70 maintained indefinitely.

This form of construction however, does not give the greatest possible efficiency, for there is no increase of flux due to the movement of the armature and consequently no 75 increase in pull at the end of the movement of the armature which produces the blow upon the diaphragm for if the momentary direction of the current is such as to polarize both ends of the armature north and to 80 cause the armature to rotate in a clockwise direction the shortening of the air gap A between one end of the armature and the magnet toward which it approaches is accompanied by a corresponding lengthening of 85 the air gap B at the opposite end of the armature so that the total or resultant air gap between the armature and the magnet which is co-operating with it remains un- 90

The efficiency of a signal actuating mechanism of this general character may however, be greatly increased by adding neutral central poles, which will cause the flux to pass through circuits in opposite quadrants as illustrated in Fig. 1. This is accomplished by simply connecting the neutral points of the two permanent magnets with the middle of the armature so that when the current is in a direction to cause both ends of the armature to be north poles the flux is divided into two separate paths each of which is one half the length of the magnets and armature and located upon diametrically opposite sides of the central pivot 10. The paths of these magnetic circuits are shown in Fig. 1 by arrows, one path being across the gap A between the armature and the pole S' of the magnet 8 and the other across the gap C between the pole S of the magnet 7 and the armature 9. When the current is reversed the flux paths change to the other quadrants of the magnets. It will therefore, be apparent that the working flux due to the alternating current alternates from one magnet to 105 the other in such a manner that the direction of the flux due to the alternating current is always in the direction of the flux of the permanent magnet and consequently no demagnetizing effect is produced. 115

Furthermore, in this construction as the air gaps A and C shorten, the flux through the quadrants increases so that an accelerated movement is given to the armature which produces a very strong impact upon the head 28 of the stems which are connected to the diaphragms of the horns.

In producing the construction illustrated in Fig. 1 any suitable type of permanent magnet may be utilized and any suitable 125

means employed for connecting the neutral points of the magnets with the central portion of the armature. In the construction illustrated herein the magnets 7 and 8 are 5 constructed of a series of laminated steel plates 30 which are suitably secured together and supported from the bottom 1 of the casting. The central or neutral portions of these magnets are connected by cross pieces 10 31, 32 in which the pivot 10 of the armature is secured.

The armature 9 preferably is of laminated structure being formed of soft iron plates 33 which are connected together at their 15 ends by pins 34, 35 and which may conveniently be connected together at their middle by the pivotal support 10. The pivotal support 10 preferably is provided with screw threaded portions 36 to receive nuts 37 20 which serve the double purpose of clamping the laminae of the armature 33 together and of securing the same to the pivotal post 10. The ends of the pivotal post 10 may be slightly reduced and mounted in bearings 25 38 in the cross piece 31, 32.

The coils 13, 14 for the alternating current may be wound on suitable spools 39 having extended bases 40 adapted to be secured to the cross pieces 31, 32 by suitable screws 41. 30 By reason of this construction a powerful and efficient signal actuating mechanism is provided which is entirely free from springs or other easily breakable parts. By so balancing the armature that its center of gravity is located at its pivot and its center of 35 percussion at the line of impact between the face 12 of the armature and the heads 28 of the diaphragm actuating rods 24, the current consumption required to operate the device is reduced to a minimum and a maximum efficiency obtained.

Furthermore, by reason of the synchronism between the alternation of the current and the normal vibration of the diaphragm 45 a mechanism is provided which will instantly cause the diaphragm to assume its normal rate of vibration and almost instantly its maximum amplitude of vibration.

While the construction is disclosed herein 50 for operating a signaling device of any desired character the vibrating mechanism is adapted to many other purposes, such for example as for operating a master vibrator for a signaling system or a rectifier for 55 transforming an alternating current to a direct current and various other uses in the art.

It is therefore to be understood that the 60 embodiments of the invention are of an illustrative character and not restrictive and that the following claims are to be given a broad interpretation adapted to cover any uses to which the invention may be applied as well as various modifications in form, 65 structure and relation of parts.

Having thus described my invention, what I claim as new and desire to secure by Letters Patent is;

1. A polarized synchronous signaling mechanism comprising a magnet, an armature located in proximity to the poles of said magnet, means for producing a magnetic flux in said armature alternately in opposite directions and means for causing said magnetic flux to pass from said armature alternately through the respective poles of said magnet only in the normal direction of the magnetic flux of the respective poles. 70 75

2. A polarized synchronous vibrating signaling mechanism comprising a pair of complementary magnets having their opposite poles facing one another, an armature reciprocably mounted intermediate of said poles, means for producing a magnetic flux in said armature alternately in opposite directions 80 85 whereby the same will pass alternately through the respective magnets in the normal direction of the magnetic flux of said magnets to cause a reciprocation of said armature and means operable by the reciprocation of said armature to produce a recognizable signal. 90

3. A polarized synchronous vibrating signaling mechanism comprising a pair of complementary magnets having their opposite poles juxtaposed, an armature mounted for bi-lateral movement between said juxtaposed poles, means for passing an alternating current around said armature to cause a magnetic flux through said armature alternately in opposite directions and alternately through the magnetic circuits of the respective magnets in the normal direction of the magnetic flux of said magnets whereby vibration will be transmitted to the armature and means operable by said armature for producing a recognizable signal. 95 100 105

4. A polarized synchronous vibrating signaling mechanism comprising a pair of complementary permanent magnets having their opposite poles juxtaposed, an armature mounted for bi-lateral movement between the juxtaposed poles of said magnets, a fixed coil surrounding said armature, means for passing an alternating current through said coil to cause a magnetic flux through said armature alternately in opposite directions and alternately through the magnetic circuits of the respective magnets in the normal direction of the magnetic flux of said magnets whereby vibration will be transmitted to the armature and means operable by said armature for producing a recognizable signal. 110 115 120

5. A polarized synchronous vibrating signaling mechanism comprising a pair of complementary magnets having their opposite poles juxtaposed, an armature pivotally mounted centrally of said magnets for bi-lateral movement, coils surrounding said 125 130

armature upon either side of the pivot of said armature and wound to cause the current passed through said coils to produce the same polarity in both ends of said armature, 5 means for passing an alternating current through said coils whereby balanced forces for turning said armature about said pivot will be produced and said turning forces reversed at each alternation of the current, 10 and means operable by the vibration of said armature to produce a recognizable signal.

6. A polarized synchronous vibrating signaling mechanism comprising a pair of complementary magnets having their opposite 15 poles juxtaposed, an armature pivotally mounted centrally of said magnets for bi-lateral movement and extending between said juxtaposed poles, means magnetically connecting the neutral portions of said magnets with the central portion of the armature, 20 means for passing the alternating current through said coils whereby two multiple half-length magnetic circuits will be produced in diametrically opposite quadrants of said magnets and the air gaps between the operating magnet poles and the armature shortened with the movement of the armature and means for causing the vibration of the armature to transmit blows to said diaphragm to produce an audible signal. 25

7. A polarized synchronous vibrating signaling mechanism comprising a pair of complementary permanent magnets having their opposite poles juxtaposed, an armature pivotally mounted centrally between said magnets for bi-lateral movement, means magnetically connecting the neutral portion of each magnet with the central portion of said armature, coils surrounding said armature upon opposite sides of the pivot of said armature and wound to cause the current 30 passing through the same to produce the same polarity at both ends of said armature, means for passing an alternating current through said coils whereby two multiple magnetic circuits, each one-half the length 35 of the magnet, will be produced in diametrically opposite quadrants of said magnets and will be caused to alternate from one pair of quadrants to the other upon each reversal of current whereby the armature 40 will be vibrated and the air gaps between said armature and the magnet poles will be shortened with the movement of the armature and means operable by the vibration of said armature to produce a recognizable 45 signal. 50

8. A polarized synchronous vibrating horn mechanism comprising a horn having a diaphragm, a pair of complementary magnets having their opposite poles juxtaposed, an 55 armature reciprocably mounted between the poles of said magnets, means for passing an alternating current around said armature to produce simultaneously the same polarity in both ends of said armature, means for causing the vibration of said armature to trans-

mit blows to said diaphragm to produce an audible signal.

9. A polarized synchronous vibrating horn mechanism comprising a horn having a diaphragm, a pair of complementary magnets having their opposite poles juxtaposed, an armature mounted for bi-lateral movement between the juxtaposed poles of said complementary magnets, stationary coils surrounding said armature wound to cause 70 a current passed through the same to produce the same polarity in both ends of said armature, yoke pieces magnetically connecting the neutral portions of said magnets with the central portion of the armature, 75 means for passing the alternating current through said coils whereby two multiple half-length magnetic circuits will be produced in diametrically opposite quadrants of said magnets and the air gaps between the operating magnet poles and the armature shortened with the movement of the armature and means for causing the vibration of the armature to transmit blows to said diaphragm to produce an audible signal. 80

10. A polarized synchronous vibrating horn mechanism comprising a pair of horns having diaphragms and means for vibrating said diaphragms including a pair of permanent magnets having their opposite poles juxtaposed, an armature reciprocably mounted intermediate of said magnets, means for passing an alternating current around said armature to create a magnetic flux through said armature and alternately 95 through the oppositely disposed magnets to cause a reciprocation of the armature and means for causing the vibration of the armature to strike blows alternately upon the diaphragms of said horns. 100

11. A polarized synchronous signaling mechanism comprising a vibratory sound producing member, a blow receiving member therefor, a pair of complementary magnets having their opposite poles juxtaposed, an armature adapted to impinge upon said blow receiving member pivotally mounted between the poles of said magnet and balanced to position its center of percussion in the line of impact with said blow receiving instrumentality, whereby vibration of the armature from its impact with said blow receiving member will be substantially eliminated and means for producing a magnetic flux in said armature alternately in 110 opposite directions to cause oscillation of said armature. 115

12. A polarized signaling mechanism comprising a diaphragm, a blow receiving instrumentality connected to said diaphragm, a pair of complementary magnets having their opposite poles juxtaposed, an armature adapted to impinge upon said blow receiving member pivotally mounted between the poles of said magnet and bal- 125 130

anced to position its center of gravity at said pivot and its center of percussion in the line of impact with said blow receiving instrumentality whereby vibration of the 5 armature from its impact with said blow receiving instrumentality will be substantially eliminated and means for producing a magnetic flux in said armature alternately in opposite directions to cause oscillation 10 of said armature.

13. A polarized synchronous vibrating mechanism comprising a magnet, an armature having its ends located in proximity to the respective poles of said magnet, means 15 for causing a magnetic flux to pass through said armature and one of the poles of said magnet only in the normal direction of the magnetic flux of said magnet to cause a

reciprocation of the armature and means for utilizing the vibration of said armature. 20

14. A polarized synchronous vibrating mechanism, comprising a pair of complementary magnets having their opposite poles facing one another, a member reciprocably mounted intermediate of said poles, means for producing a magnetic flux in said member alternately in opposite directions whereby the magnetic flux of said member in coöperation with the fields of the magnets will cause a reciprocation of said member and means for utilizing the vibration of said member. 25

In testimony whereof, I have signed my name to this specification. 30

DANIEL S. WILSON.
